DOCUMENT REPRODUCING UNIT

Mario Bellini, Milan, Italy, assignor to Ing. C. Olivetti & C., S.p.A., Ivrea, Torino, Italy

Filed Oct. 13, 1967, Ser. No. 9,033

Term of patent 7 years

Claims priority, application Italy Apr. 13, 1967

Int. Cl. D16—05

U.S. Cl. D61—1

Fig.1

Fig.2

Fig.3

FIGURE 1 is a perspective view showing the top, front and right side of a document reproducing unit showing my new design;

FIGURE 2 is a similar view as FIG. 1 showing a document support in raised position, and

FIGURE 3 is a perspective view of the unit, showing the back and left side.

I claim:

The ornamental design for a document reproducing unit, substantially as shown and described.
